UNITED STATES PATENT OFFICE.

WILLIAM HARLEY PORTER, OF LIMA, OHIO.

FILE OR BINDER.

SPECIFICATION forming part of Letters Patent No. 440,499, dated November 11, 1890.

Application filed May 16, 1889. Serial No. 311,183. (No model.)

To all whom it may concern:

Be it known that I, WILLIAM HARLEY PORTER, a citizen of the United States, residing at Lima, in the county of Allen and State of Ohio, 5 have invented a new and useful Improvement in Files or Binders for Newspapers, of which the following is a specification.

My invention relates to improvements in files or binders for newspapers, and its object 10 is to bind together a number of newspapers into a book or package of convenient size for distribution to agents in such a manner that one or more papers may be torn or removed therefrom without displacing the remainder, 15 and so that those so removed for sale at retail will, by the operation of removing them from the file, be mutilated or marked in such a manner as to prevent their being returned to the publishers by such distributing agents as un- 20 sold papers. This imposition is very wide- spread, and to prevent it some publishers have resorted to the plan of printing upon a corner of the margin of the paper a request that the purchaser will, after buying the same, tear 25 off such corner, so as to mutilate the same and prevent its return to them, as aforesaid; but this plan is open to the objection that its efficiency depends wholly upon the compli- 30 ance with this request. My invention entirely obviates this objection by causing the very act of removing the paper for sale to put the desired mark upon it.

I attain my object by means of a clasp or binder made of heavy paper, bristol-board, or 35 other suitable material, which is illustrated in the accompanying drawings, in which—

Figure 1 is a detached view of my said file or binder before the flap forming a part of the same is gummed down, as hereinafter de- 40 scribed and Fig. 2 is a view of the same as it appears after that operation. Fig. 3 is a view of said file or binder as it appears when at- tached to a package of papers so as to bind them together in the manner described.

45 Similar letters represent similar parts throughout the several views.

A represents a clasp or binder, which is made of the material mentioned and so folded that its lips a a will project over and clasp 50 the blank margin of the papers, so as to hold snugly within them a package of papers of

the desired thickness. The clasp is held in place and the package of papers bound together and retained firmly within it by means of metallic staples B B, which are driven 55 through the clasp and papers and clinched by suitable machinery. The upper lip of said clasp is made wider than the lower one, as shown in the figures, the same being provided with a flap b, so that after the staples have 60 been clinched this flap may be folded back upon the clasp and gummed down upon it over the clinched ends of the staples; or, if preferred, held in place over them by a sepa- 65 rate smaller paper or seal pasted across both flap and clasp, thus forming a seal, so as to in- 70 dicate whether or not the staples have been opened or the clasp tampered with. In prac- tice said binder is most conveniently applied to the upper right-hand corner of the package 75 of papers. When so applied, it forms a file or binder which holds the papers together in a neat, compact, and easily-handled package which contains a known number of papers, and thus greatly facilitates the counting of the 80 same, and from which as the papers are sold they may be separately torn out, leaving the remainder of the package compact. The re- 85 moval of a paper from the file so tears and disfigures the margin of the same as to per- manently mark and identify it as a paper which has been sold out of the original pack- 90 age, so as to prevent the agent handling the same, if so disposed, from afterward return- 95 ing and obtaining credit for the same as an unsold paper.

Having thus described my invention, what I claim as new, and desire to protect by Letters Patent, is—

1. In combination with a series of sheets, a 90 holder provided with the jaws between which the sheets are clasped, a fastening device passed through the jaws and contained sheets, and a seal applied to the outer side of one of the jaws over the end of the fastening device, 95 substantially as described.

2. In a newspaper-file, the body A, provided with the two jaws adapted to clasp the sides of the package of papers, in combination with the staples B, passed through said jaws and 100 the contained package and having the ends of its legs bent down upon the body, and the

seal *b*, covering said bent ends of the legs, substantially as described.

3. The package, the body *A*, having the two jaws, one of which is provided with the lip *b*, flexibly connected thereto, in combination with the fastening device passed through said jaws and the package and having its end bent

laterally upon the body in position to be covered by the lip, substantially as described.

WILLIAM HARLEY PORTER.
